HOLDERS AND FILTERS FOR TOBACCO SMOKING

Merwin Gerard and Seeleg Lester, Los Angeles, Calif., assignors, by mesne assignments, to Aquafilter Corporation, New York, N.Y., a corporation of Delaware

Application September 21, 1954, Serial No. 457,349

5 Claims. (Cl. 131—208)

The present invention relates to smoking apparatus, and more particularly to holders and filters for articles embodying tobacco, such as cigarettes, cigars and pipes, which are effective in removing harmful ingredients from tobacco smoke during the process of smoking.

Accumulated evidence by competent medical authorities indicates that the death rate from diseases of the coronary arteries and the death rate from cancer are much higher among persons with a history of regular cigarette smoking than among persons who did not smoke. Nicotine is believed to be the primary agent in cigarette smoke hastening death due to coronary artery disease. Attempts have been made to reduce the amount of nicotine and other ingredients in tobacco smoke absorbed by the smoker by causing the smoke to pass through filters, which are either embodied in a filter type cigarette or in a holder for the cigarette, cigar or pipe tobacco. Such filters remove a certain proportion of nicotine and tars from the smoke, but the amount remaining and passing into the smoker's system is still far greater than a safe value and is capable of causing objective damage to the heart.

Mere reduction by a filter of the nicotine reaching a smoker is not enough, unless the filter reduces the nicotine in the smoke to at least the safe value given above.

In addition to nicotine, the tars absorbed by a person may have an adverse effect on his health. Moreover, the relatively high temperatures of the smoke passing into the smoker's mouth may produce harm. It is known that such high temperatures produce a burning or a biting sensation, and render smoking less enjoyable.

In accordance with the present invention there is provided a smoking filter adapted to effectively remove from smoke, such as cigarette smoke, the above harmful ingredients, and bring the amount of such ingredients passed by the filter down well within a tolerable limit. At the same time this effect is accomplished without significantly removing moisture from the smoke, and without impairing the enjoyment of smoking. These effects and benefits are obtained by providing a filter comprising a mixture of fibrous material, a portion of which is non-absorbent to liquid, and a portion of which is absorbent. This fibrous filter is further substantially saturated with a liquid in which nicotine is miscible. In this filter it is primarily the liquid that acts to treat the smoke, while the non-absorbent fibers provide, in the otherwise saturated filter, the necessary passages for drawing smoke therethrough. Whereas the presence of absorbent fibers in a smoking filter would normally tend to remove natural moisture from the smoke, this adverse effect is not obtained by the present filter, due to the fact that such fibers are here substantially saturated with liquid.

Accordingly, it is an object of the present invention to provide an improved filter to be used by persons smoking tobacco, which is capable of reducing the amount of nicotine in the smoke passing to the person's mouth to a safe value.

Another object of the invention is to provide an improved filter to be used in connection with smoking cigarettes, cigars, and the like, which is capable of removing a larger quantity of tars and other potentially harmful substances from the smoke, rendering the smoke entering the person's mouth relatively harmless to the person's system.

5 A further object of the invention is to provide an improved filter to be used by persons smoking tobacco, which not only is capable of effectively removing harmful ingredients from the smoke, but which cools the smoke considerably.

10 Yet another object of the invention is to provide a filter to be used by a person smoking tobacco, which does not become clogged nor lose its effectiveness after repeated use.

15 Still a further object of the invention is to provide a filter effective in removing nicotine, tars and other matter detrimental to the health of the smoker, in which the filter offers relatively low resistance to the passage of smoke therethrough.

20 Still another object of the invention is to provide a holder or filter for articles of tobacco, in which the smoke is prevented from by-passing the filter, all of it being forced to pass through the filter.

25 Still another object of the present invention is to provide a smoking filter for cigarettes, or the like, which removes a substantial portion of the tars and nicotine from the smoke, without materially reducing the moisture content thereof.

30 This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

35 Referring to the drawings:

Figure 1 is a longitudinal section through a cigarette holder and filter embodying the invention;

Fig. 2 is an exploded sectional view of the holder and filter disclosed in Fig. 1;

40 Fig. 3 is an enlarged longitudinal section through the cigarette holding and ejecting portion of the device disclosed in Figs. 1 and 2, the ejector occupying another operative position;

Fig. 4 is an enlarged cross-section taken along the line 4—4 on Fig. 1;

Fig. 5 is an enlarged cross-section taken along the line 5—5 on Fig. 1;

Fig. 6 is an enlarged cross-section taken along the line 6—6 on Fig. 1;

Fig. 7 is an enlarged cross-section taken along the line 7—7 on Fig. 1, the forward end of the filter cartridge being omitted.

45 The cigarette holder and filter disclosed in the drawings has been particularly designed for use in holding cigarettes and filtering the products of combustion emanating therefrom. It is to be understood, however, that such specific illustration represents merely one embodiment of the invention, which can be readily adapted for use in the smoking of cigars and pipe tobacco. Moreover, the filter portion of the apparatus can be used in connection with articles of tobacco, such as cigarettes, in the absence of the holder.

50 As specifically disclosed, the cigarette holder 10 is of generally tubular form, being made in several sections. Thus, a rear body portion 11 may be made of a suitable material, such as a synthetic resin, this rear body portion

having a metallic bushing 12 pressed into a forward chamber portion 13, adapted to receive a filter cartridge. The bushing has an intermediate outwardly directed flange 14 abutting the end of the body section 11, and also a forward externally threaded position 15 adapted to mesh with internal threads provided on the rear part 16 of a forward tubular body section 17 adapted to abut the bushing flange 14.

The rear body member 11 has a central passage 18 therethrough through which smoke from the chamber 13 can be drawn, this body member having a mouthpiece 19 of suitable form that can be held conveniently in the mouth of the smoker. The forward body member 17 has a reduced diameter cylindrical portion 20 that forms an inner shoulder 21 with the remainder of the forward body member. A cigarette C is insertable within the reduced diameter portion 20 of the forward body member, the rearward movement of the cigarette into this body member being limited by its engagement with a transverse pin or ejector rod 22 extending across the reduced diameter portion 20 through opposed axial, inclined cam slots 23 therein and into a circumferential groove 24 in an ejector sleeve 25 that is rotatably and axially movable upon the reduced diameter portion. The ejector sleeve 25 may occupy a rearward position in engagement with a shoulder 26 on the forward member 17, allowing a cigarette to be inserted and retained within the cigarette holding portion 20 of the forward body member (Fig. 1), or the ejector sleeve 25 may be turned, which will effect axial forward feeding of the sleeve and the ejector rod 22 along the reduced diameter portion and within the cam slots, in order to effect removal of the cigarette from the holder (Fig. 3).

Despite the fact that the ejector rod 22 extends through the cam slots 23 and into the circumferential groove 24 in the ejector sleeve, it cannot move relative to the ejector sleeve 25 since it is forced into holding engagement with the base 24a of the ejector sleeve groove 24, as, for example, by inserting the rod 22 through the cam slots 23 and into the groove 24 and then striking it in a direction transversely of the longitudinal axis of the holder, which will press its ends firmly against the base 24a of the groove, uniting the rod to the ejector sleeve.

Inadvertent movement of the ejector sleeve 25 along the forward body portion 20 is prevented by a retainer device, which may be in the form of a split snap or contractile ring 30 received within a circumferential groove 31 in the ejector sleeve 25 and frictionally engaging the periphery of the reduced diameter portion 20 of the forward body member 17.

The forward portion of the rear body member 11, the bushing 12 pressed into the rear body member, and the rear portion of the forward body member 17 together form a chamber 13 for the reception of a filter device 32 through which all of the cigarette smoke drawn into the holder must pass before entering the smoker's mouth. The filter device includes a cartridge 33 of generally cylindrical form, having a rearward portion 34 adapted to slidably fit within the bushing 12 and a forward portion 35 of greater diameter than the rearward portion, for reception within the chamber part provided by the forward body member, which is of greater diameter than the internal diameter of the bushing 12. The rearward and forward portions 34, 35 of the cartridge are interconnected by a transverse shoulder 36 adapted to abut and seal against the forward end 37 of the metallic bushing. The filter device 32 is insertable within the bushing 12 when the forward body member 17 has been unthreaded and removed completely from the bushing, the forward body member then being threaded onto the bushing to the extent at which its rearward end abuts the flange 14, at which time the internal shoulder 21 will engage the forward end of the cartridge 33 and compress the shoulder 36 into sealing engagement with the end 37 of the bush-

ing, thereby preventing passage of smoke from the cigarette in the holder around the exterior of the cartridge.

The cartridge 33 contains a filtering material 38, which is confined therein against endwise movement by a rear 5 inwardly directed flange 39 of the cartridge, across which extends a diametrically disposed cross-piece 40. The filter material 38 may be inserted through the forward end of the cartridge until the rear portion of the filter material 10 engages the flange 39 and cross-piece 40, whereupon forward tabs 41 at the peripheral portion of the cartridge may be bent inwardly, to partially overlap the forward end 15 of the filter material and prevent its axial shifting in a forward direction.

It is to be noted that the forward face of the filter material 38, as well as its rearward face, is comparatively 15 free from obstruction by the end portions 39, 40, 41 of the cartridge, to provide large spaces for the passage of smoke through the filter and cartridge, and thereby reduce the resistance to the drawing of smoke through the filter and into the smoker's mouth.

The filter material 38 consists of fibrous matter, a portion 20 of which is capable of retaining water, glycerine, or some other moisture, which is miscible with the nicotine in the smoke being drawn therethrough. It has been 25 found that a filter material consisting of a mixture of water-absorbent fibers and non-water-absorbent fibers substantially saturated with water is effective in reducing the nicotine passing to the smoker's mouth well below the safe value of 0.65 milligram per cigarette. An exceedingly large percentage of the nicotine in the smoke is removed upon its contact with the water absorbed and present in the filter. The combination of fibers used is such 30 that a very large number of interstices or passages is present through the entire mass of filter material through 35 which smoke can be drawn with comparatively low resistance. Not only does the filter material remove a very great percentage of the nicotine in the smoke, but it also is effective in removing a very great proportion of the tars and other harmful substances in the smoke, in 40 addition to effectively cooling the smoke to a temperature that is only slightly higher than room temperature.

The specific filter material used can consist of a mixture 45 of non-absorbent cotton fibers and absorbent cotton fibers. If the liquid with which the filter material is to be saturated is water, then the absorbent fibers have the characteristic of being capable of absorbing a relatively large amount of water, whereas the non-absorbent fibers will absorb very little, if any, water. In view of the mixture between the two types of cotton fibers referred 50 to, a relatively large amount of water is available in the absorbent fibers, such water, however, being penetrated by the non-water-absorbent fibers, which provide passages through which the smoke can be drawn. During such passage through the filter, the smoke contacts a large 55 surface of water, the nicotine mixing with the water and remaining in the filter.

A specific example of filter material used has been a mixture of fifty percent by weight of absorbent cotton fibers and fifty percent by weight of non-absorbent cotton 60 fibers, which are intimately mixed with each other, after which they may be placed in a suitable form or shape for insertion in the holding or retaining cartridge 33.

The above specific proportions of absorbent and non-absorbent cotton fibers can be varied to some extent while 65 still providing a filter material within the filter cartridge capable of effectively removing the harmful materials from the tobacco smoke.

The mixture of the two types of cotton fibers may be 70 rolled into a generally cylindrical form having a diameter that will permit its insertion into the retaining cartridge 33. The cylinder material is cut into the proper length for reception completely within the cartridge. In order to facilitate cutting and the insertion of the cylinder of filter material into the cartridge 33, it is preferred to coat 75 the surface of the cylinder material with a stiffening

material that may penetrate the surface to a small extent, as, for example, to the extent of about $\frac{1}{32}$ to about $\frac{1}{16}$ of an inch. As an example, pectin has been found to be a suitable coating material upon the periphery of the cylinder of filter material. Such coating not only enhances the cutting of the filter material to the proper lengths and facilitates its insertion in the cartridge 33, but the pectin will immediately dissolve upon wetting of the filter material, as with water, the dissolved pectin then allowing the cylinder of material 38 to swell under the action of the water, or other moisture, until it expands into intimate contact with the inner wall of the cartridge 33, both at its smaller and larger diameter portions 34, 35. Moreover, it has been found that the pectin in the filter also acts to hold nicotine in suspension and aids in the removal of the latter, as well as tarry materials, from the smoke passing through the filter. In view of the wetting or saturation of the filter material 38 with water, glycerine, or other equivalent material, and its expansion and swelling into intimate contact with the inner wall of the cartridge 33, assurance is had against bypassing or channelling of the smoke between the periphery of the cylinder of filter material and the inner wall of the cartridge.

In the use of the apparatus, suction applied by the smoker to the mouthpiece 19 will draw smoke from a cigarette C, such smoke passing through the filter material 38 and thence into the chamber 13 in the rear body member 11 rearwardly of the filter cartridge 33. Some moisture will be contained in the smoke passing into this chamber portion and it is desired that such moisture not be removed from the holder. Accordingly, a moisture trap is formed in the holder. Thus, a cylindrical sleeve of metal 42, having a much smaller diameter than the chamber 13, may be pressfit in the central passage 18 through the rear body member, this sleeve extending forwardly into the rear portion of the chamber 13 and being axially spaced from the cartridge 33. The smoke and moisture that might be drawn through the filter will first pass into the rear of the chamber 13, the water tending to drop out of the smoke and into the lower portion of the chamber. The filtered smoke itself will then pass through the sleeve 42 and the central passage 18 in the mouthpiece 19 into the mouth of the smoker.

In the use of the apparatus, the filter mass 38 is wetted with water. In one size of filter suitable for smoking the average type of cigarette, about fifteen drops of water are sufficient to saturate the filter material 38. The moisture laden cartridge 32 is then inserted in the bushing 12 and the forward holder member 17 screwed upon the bushing, so as to securely clamp the shoulder 36 of the cartridge 33 against the end 37 of the bushing. The ejector sleeve 25 is disposed in its rearward position, allowing the insertion of a cigarette C in the forward end 20 of the holder. The cigarette is then ignited and smoked in the usual fashion, the smoke passing through the filter, with some of the harmful ingredients in the smoke being removed during such passage, any excess moisture in the smoke dropping out of the rear trap portion of the chamber 13 prior to entering the passage 18 through the mouthpiece 19.

The smoke is cooled in passing through the filter device 32 to a considerable extent, the cooling action being substantially enhanced by the high heat conductivity of the aluminum cartridge 33 and bushing 12, as well as by the sleeve 42 forming part of the moisture trap. It appears that moisture in the air drawn through the filter material 38 is also absorbed by the absorbent fibers, tending to retain the filter material in a suitable wet state for most effective filtering of the smoke passing therethrough.

A cartridge and filter 32 can be used for a plurality of cigarettes without losing its effectiveness. A single filter device 32 is effective for the smoking of a package of cigarettes containing twenty cigarettes.

The effectiveness of applicants' filter is demonstrated by actual tests conducted with unfiltered cigarettes, with cigarettes having filters attached thereto, and unfiltered cigarettes smoked through use of a cigarette holder embodying a filter.

The following table gives the amounts of nicotine remaining in the smoke at the discharge ends of well-known brands of cigarettes:

Table I

Nicotine and tars in milligrams recovered in main stream of king size cigarettes smoked in 10 approximately 35 millimeter puffs, each lasting 2 seconds and spaced 1 minute between puffs.

Brand	Nicotine	Tars
Brand A (non-filter type)	2.6	20
Brand B (filter type)	1.8	8
Brand C (filter type)	2.3	14
Brand D (filter type)	2.7	22

The above values in Table I were secured from averages obtained on cigarettes purchased in the open market at various tobacconists.

King size brand A cigarettes smoked without filter holders furnished 2.6 milligrams of nicotine and 20 milligrams of tars average per cigarette according to Table I above. The following table gives the result of smoking king size brand A cigarettes through various well-known filter holders, as shown. The nicotine and tars were recovered at the outlet of the filter holder when smoking brand A cigarettes in 10 approximately 35 millimeter puffs, each puff lasting 2 seconds and spaced 1 minute between puffs:

Table II

Holder	Nicotine (milli- grams)	Percent nicotine passing through	Tars (milli- grams)	Percent tars passing through
Holder X	2.16	83	16.0	80
Holder Y	1.82	70	12.8	64
Holder Z	1.01	61	12.0	60
Applicants	.21	8	4.8	24

From the foregoing Table II, it is evident that applicants' holder and filter (consisting of about 50% by weight of absorbent cotton fibers and about 50% by weight of non-absorbent cotton fibers) are effective in reducing the nicotine in the smoke to an average of about 0.21 milligram per cigarette, the cigarette in each instance in the above table having been smoked through until approximately a one-inch length of butt remained.

The following table discloses the effectiveness of applicants' filter holder after use in repeated smoking of cigarettes:

Table III

Percentage of nicotine passing through various filter holders on smoking brand A king size cigarettes after 1, 10 and 20 (1 pack), suggesting the endurance of filter holder effectiveness.

Holder	1 Ciga- rette, percent	10 Ciga- rettes, percent	20 Ciga- rettes, percent
Holder X	83	88	91
Holder Y	70	63	51
Holder Z	61	54	50
Applicants	8	7	7

It is evident from the above table that applicants' filter remains essentially constant in performance of nicotine removal from the first to the last of twenty cigarettes in a pack, applicants' filter having a long actual life of effectiveness. The other filter holders continue to permit a percentage of nicotine to pass through the filter that is

essentially above the safe limit of nicotine that can be absorbed by the human system without damage to the heart.

The following table is a comparison between the rise in temperature in Fahrenheit degrees over prevailing room temperature measured on the stream of smoke leaving the holder after a king size brand A cigarette is half consumed (mid-point), and again when it is burned down so as to leave an approximately 1 inch long butt:

Table IV

Holder	Average rise in Fahrenheit degrees above temperature of room.	
	At mid-point	At Butt
Holder X	24	32
Holder Y	16	29
Holder Z	18	30
Applicants	4	9

From the above Table IV it is quite evident that applicants' filter is exceedingly effective in cooling the main stream of smoke leaving the holder. Applicants' filter and holder furnish a three to four times cooler smoke, as measured by lesser temperature rise above room temperature.

The inventors claim:

1. A filter for use in smoking tobacco, comprising a 30 container having a continuous sidewall construction, a mixture of moisture absorbent fibers and substantially moisture non-absorbent fibers positioned within said container, and a liquid miscible with nicotine substantially saturating said absorbent fibers and thereby swelling said mixture into firm contact with said sidewall, said non-absorbent fibers affording minute passages through which smoke may be drawn with relatively low resistance when said filter is wet by said liquid, said liquid being adapted to treat the smoke.

40

5

10

2. A filter as set forth in claim 1, wherein said mixture of fibers is approximately 50% by weight of moisture absorbent fibers and approximately 50% by weight of substantially moisture non-absorbent fibers.

3. A filter as set forth in claim 1, wherein at least said moisture absorbent fibers are cotton fibers.

4. A filter as set forth in claim 1, wherein said liquid is water.

5. A filter as set forth in claim 1, wherein said mixture of fibers is approximately 50% by weight of moisture absorbent cotton fibers and approximately 50% by weight of substantially moisture non-absorbent cotton fibers, and said liquid is water.
